UNITED STATES PATENT OFFICE

157,609

COOKSTOVE

Gabriel Levine, West Hartford, Conn.

Application August 18, 1948, Serial No. 148,174

Term of patent 7 years

(Cl. D81—10)

To all whom it may concern:

Be it known that I, Gabriel Levine, a citizen of the United States, residing at West Hartford, county of Hartford, State of Connecticut, have invented a new, original, and ornamental Design for Cookstove, of which the following is a specification, reference being had to the accompanying drawing, forming a part thereof.

The figure is a perspective view of a cookstove, showing my new design. The left-hand side of the figure not shown is substantially plain.

I claim:

The ornamental design for a cookstove, substantially as shown, and described.

GABRIEL LEVINE.
